UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

YARN-FEEDING MECHANISM FOR KNITTING-MACHINES.

1,168,549.

Specification of Letters Patent.

Patented Jan. 18, 1916.

Application filed August 20, 1914. Serial No. 857,759.

To all whom it may concern:

Be it known that I, EDISON E. RANDALL, a citizen of the United States, residing at Kankakee, county of Kankakee, State of Illinois, have invented an Improvement in 5 Yarn-Feeding Mechanism for Knitting-Machines, of which the following description, in connection with the accompanying drawing, is a specification, like characters 10 on the drawing representing like parts.

This invention relates to yarn feeding mechanism for knitting machines in which a plurality of yarns are fed to the needles and in which one or more of the yarns so 15 fed are supplied at and during required intervals as for example in re-inforcing different sections of the fabric being knitted. The yarn or yarns supplied in the regular 20 course of knitting are herein referred to as "main" yarn and the yarn or yarns supplied at intervals are referred to as the "re-inforcing" yarns. Various means have been employed for causing the reinforcing yarns 25 to come into action and be fed along with the main yarn at the required times and the invention in its broader aspect is independent 30 of any such particular form of mechanism.

The object of the invention is to provide 35 a stop-motion mechanism actuated upon the failure of the reinforcing yarn to be brought in and fed along with the main yarn when required and also actuated upon the breakage of the reinforcing yarn while being fed in.

This and other objects of the invention will appear more fully from the accompanying description and drawings and will be particularly pointed out in the claims.

40 The drawings show so much of an ordinary type of yarn feeding mechanism and stop motion mechanism together with the upper portion of the frame work of knitting machine as is necessary to an understanding of a preferred form of the present 45 invention shown in connection therewith.

In the drawings, Figure 1 is a side elevation of the upper end of the framework of a knitting machine, with the supported 50 yarn feeding mechanism and stop motion mechanism; and Fig. 2 is an end elevation of the upper portion of the yarn-feeding mechanism, both figures showing a preferred form of the present invention. Fig. 55 3 is a side elevation of a portion of the con-

struction shown in Fig. 1 with the parts illustrated on the same scale as in Fig. 2.

The invention is applicable to various types of knitting machines and so it is not necessary to illustrate or describe the knitting machine itself or the driving connections usually controlled by the stop motion mechanism.

The invention is applicable to various forms of yarn-feeding mechanism in which 65 there is a main yarn-feeding mechanism and a reinforcing yarn-feeding mechanism. Such mechanisms are common and the reinforcing yarn is brought into action and fed along with the main yarn in various ways. 70 In some cases the reinforcing yarn is brought alongside of the main yarn into frictional engagement therewith so as to be drawn frictionally by the main yarn to the needles. In some cases the reinforcing 75 yarn is wrapped or wound by suitable devices about the main yarn so as to insure its engagement therewith and its being fed along therewith to the needles. In other cases the reinforcing yarn is not only 80 wrapped about but is tied or knotted to the main yarn when brought into action so as to be fed along therewith.

The present invention is illustrated in 85 connection with the latter type of yarn-feeding mechanism, such for example as is shown in the patent to Mayo, No. 726,229, granted April 21, 1903 and to which reference may be made for a more detailed disclosure of this type of yarn-feeding mechanism. Yarn-feeding mechanisms have also 90 been provided with stop motion mechanisms so that upon the breakage of the yarn the machine would be stopped. The present invention makes use of any suitable type of 95 stop motion mechanism and there is herein shown a stop motion mechanism of the type illustrated in the patents to Wilcomb, No. 698,089, No. 698,091, and No. 698,090, granted April 22, 1902.

100 The knitting machine as already stated is not illustrated but the post 1 extends upwardly from the framework thereof and has rigidly secured thereto and supported thereabove the vertical supporting post 2 on 105 which both the main and reinforcing yarn-feeding mechanisms are supported. At the right are shown the usual cop supports 3 with the cops or supplies of yarn. A post 5 extending upward from the framework of 110

the machine usually centrally of the cop-
5 supports 3, has mounted thereon, the main
elements of the stop motion mechanism
from which the rod 6 extends downwardly
10 and is connected in a usual and suitable
manner with the driving elements of the
machine so that when moved the machine
will be stopped. Another post 7, extended
15 upwardly from the frame work serves to
support and position certain of the me-
chanism as will be clear from the drawing.

Any required number of reinforcing
20 yarns may be supplied as required by the
nature and character of the work. Two
such mechanisms are shown for a conven-
ient disclosure of the invention and as they
25 are duplicates throughout excepting in so
far as some detailed features of the present
invention are concerned, it will be necessary
30 to describe but one of these mechanisms and
as each is similar to that illustrated in the
Mayo patent already referred to, it will be
unnecessary to describe it in detail.

The main yarn as shown, comprises two
25 runs extending from the cops 4—4 shown in
Fig. 1, but any number of runs may be in-
cluded in the main yarn as required. These
30 runs 8 and 9 extend upward from the cops
between the usual guide fingers 10 and
feeler fingers 11 on the stop motion me-
chanism and extend through guide eyes on the
35 arms 12 and extend to the main yarn-feed-
ing mechanism.

This mechanism which is shown in dupli-
35 cate, comprises a head 13 secured to the
post 2 and supporting at its end a fixed
tubular yarn guide 14 terminating in a
tapering nose 15. Through these yarn
40 guides the main yarn runs in succession to
the needles of the knitting machine. If
however one of the main yarns breaks or
45 runs out, its corresponding feeler finger 11
is released and falls away from the coöper-
ating guide 10 actuating in the well known
manner, the rod 6 to stop the machine. The
50 reinforcing yarn of which two runs are
shown and consequently two reinforcing
yarn feeding mechanisms is brought into
connection with the main yarn at the re-
quired times under the control of suitable
55 automatic or pattern mechanism in a fa-
miliar manner. In the construction shown
which is that of the Mayo patent referred
to, the run of reinforcing yarn 16 or 17
60 extends from its supply, (not illustrated),
through a guide 18 mounted eccentrically
on the tubular rotary carrier 19 which is
journalized concentrically on the main yarn
65 guide 14. This carrier 19 is provided with
a pinion 20 in mesh with a gear segment
21 supported and operated on the head 13.
When the reinforcing yarn is to be thrown
70 in, this gear segment is actuated to carry the
yarn guide 18 around the nose 15 and thus
wind the end of the reinforcing yarn around

the main yarn. At the same time a knot-
tying instrumentality 22 is brought into ac-
tion and ties a knot in the end of the rein-
forcing yarn about the main yarn. When
70 the reinforcing yarn is to be cut out, the
yarn guide 18 brings the reinforcing yarn
into the field of action of a cutting and
clamping instrumentality, 23 which severs
the yarn and clamps and holds the end ex-
tending from the guide means. These means
75 for bringing the yarn feeding mechanism
into action, tying a knot in the reinforcing
yarn about the main yarn and cutting out
the main yarn, form in themselves, no part
80 of the present invention and are described
in detail in the said Mayo patent.

It will now be seen that if the automatic
or pattern mechanism calls for the intro-
duction of a reinforcing yarn and for any
reason the instrumentality concerned fails
85 to secure such an engagement of the end of
the reinforcing yarn with the main yarn as
to cause the reinforcing yarn to engage and
be brought along with the main yarn, im-
perfect work will result, or, if after the
90 reinforcing yarn has begun feeding in, it
fails or becomes broken before it is cut out,
imperfect work will also result. The pres-
ent invention provides means for actuating
95 the stop motion mechanism upon the occur-
rence of either of these events, and a pre-
ferred form of mechanism embodying the
invention and adapted for use in connection
100 with the type of main and yarn reinforcing
mechanism illustrated will now be described.

A spring catch herein shown as a bell
crank lever, is fulcrumed on the head 13
105 at 24 and has its longer arm 25 extending
out and seated in a notch in the plate 26
at the front of the head while its shorter
arm 27 is pivoted to the link 28. This link
110 in turn is pivoted to a lever 29 fulcrumed
at 30 on the post 7. The link 29 is con-
nected at its opposite end with a rod 31
which actuates the stop motion mechanism
in the same manner as it is actuated upon
115 the dropping of one of the feeler fingers 11.
A spring 32 connecting the link 28 to the
head 13 acts to elevate the longer arm 25
of the catch when released from its notch
so that when the catch is released from the
120 notch by the connections described, the rod
31 will actuate the stop motion mechanism.
In the construction illustrated but one catch
is employed for both of the reinforcing
125 yarn-feeding mechanisms and it is brought
out of its notch and the stop motion me-
chanism actuated when either of the rein-
forcing yarns fails to come into action or breaks
while being fed in.

In connection with the upper of the
two reinforcing yarn-feeding mechanisms
shown, a movable feeler 33 is employed and
consists of a light arm pivoted at 34 to the
head and having an offset portion extending
130

directly beneath the yarn guide 18 when in feeding position. This feeler is so mounted that when the reinforcing yarn is running it will rest against the yarn and be supported from dropping thereby, but being so nearly vertical in this position it creates but little pressure on the yarn. A pin 35 projects laterally from the feeler 33. A latch 36 is fulcrumed at 37 to the head. 10 The outer end 38 of the latch is hook shaped as shown in Fig. 2 and is located above the pin 35, in such position that when the reinforcing yarn is fed in, the pin 35 will just clear the latch if the feeler 33 drops. 15 The opposite end of the latch is beneath the projection of the knot-tying instrumentality 22 so that when the reinforcing yarn is running, the latch will be held with its outer end elevated in position shown in Figs. 1 20 and 2 while a spring 39 connecting the latch to the head tends to move the free end of the latch downwardly.

The operation will now be readily understood by anyone familiar with this type of 25 yarn-feeding mechanism. When the main yarn is running and the reinforcing yarn is out, the yarn guide 18 is in diametrically opposite position to that shown in Fig. 1 with the end of the reinforcing yarn 30 clamped in the instrumentality 23; the knot-tying instrumentality is elevated; the latch 36 is drawn downwardly under the influence of the spring 39 and its free end 38 is 35 engaging the pin 35 and holding the feeler 33 from falling. When the call comes to feed in the reinforcing yarn, the mechanism described is actuated causing the guide 18 to carry the end of the reinforcing yarn about the main yarn; the knot-tying instrumentality 22 seizes the reinforcing 40 yarn and drops, tying a knot about the main yarn; the instrumentality 22 in dropping, contacts with the end of the latch 31 raising its end 32 and releasing the feeler 33 so that it rests against and is supported by the reinforcing yarn now feeding in.

But if the mechanism has failed for any 50 reason to work and the end of the reinforcing yarn has not come into engagement with or been tied to the main yarn so as to be fed along therewith, immediately the latch 38 is raised, the feeler 33 finding no reinforcing yarn to support it, drops and strikes against the catch 25, knocking it out 55 of its notch and so actuating the stop motion mechanism. So also, if the reinforcing yarn is properly started to feed in with the main yarn and after running for a time breaks or runs out, the feeler 33 left unsupported will drop and in a similar manner 60 actuate the stop motion mechanism.

The connections for the lower of the two 65 reinforcing yarn-feeding mechanisms shown are similar to that already described except that a slight change is made in order to en-

able the feeler to act upon the single catch 25 already described. For this purpose the lower feeler 33 has its lower end cam shaped as at 40. A lever 41 is fulcrumed at 42 on the lower head and has its upper end directly behind the free end of the catch 25 and its lower end in the path of the cam shaped end 40 of the feeler 33. Hence when the lower feeler 33 drops upon the failure of its reinforcing yarn properly to 70 be fed in, or upon the breakage or the running out of the yarn or yarns feeding in, the cam 40 acting against the lever 41 will knock off the latch 25 and actuate the stop motion mechanism as before.

Having fully described my invention, what I claim as new, and desire to obtain by Letters Patent is:

1. A machine of the character described comprising in combination, main yarn-feeding mechanism, reinforcing yarn-feeding mechanism, means for automatically bringing into action said reinforcing yarn-feeding mechanism, stop motion mechanism, and means for actuating said stop motion mechanism upon the failure of the reinforcing yarn to feed in when its feeding mechanism is brought into action.

2. In a machine of the character described comprising in combination, main yarn-feeding mechanism, reinforcing yarn-feeding mechanism, means for automatically bringing into action said reinforcing yarn-feeding mechanism, stop motion mechanism, and means for actuating said stop motion mechanism upon the failure of the reinforcing yarn to feed in when its feeding mechanism is brought into action or upon the failure of the reinforcing yarn while being fed in.

3. A machine of the character described, comprising in combination, main yarn-feeding mechanism, reinforcing yarn-feeding mechanism, means for automatically causing the reinforcing yarn to engage and be tied to the main yarn to feed along therewith, stop motion mechanism, means for actuating said stop motion mechanism upon the failure of the reinforcing yarn to engage and be tied to and fed along with the main yarn.

4. A machine of the character described, comprising in combination, main yarn-feeding mechanism, reinforcing yarn-feeding mechanism, means for automatically causing the reinforcing yarn to engage and be tied to the main yarn to feed along therewith, stop motion mechanism, means for actuating said stop motion mechanism upon the failure of the reinforcing yarn to engage and be tied to and feed along with the main yarn or upon the failure of the reinforcing yarn while being fed in.

5. A machine of the character described, comprising in combination, main yarn-feeding mechanism, reinforcing yarn-feeding

mechanism, means for automatically causing the reinforcing yarn to engage the main yarn to feed along therewith, stop motion mechanism, means for actuating said stop motion mechanism upon the failure of the reinforcing yarn to engage and feed along with the main yarn.

6. A machine of the character described, comprising in combination, main yarn-feeding mechanism, reinforcing yarn-feeding mechanism, means for automatically causing the reinforcing yarn to engage the main yarn to feed along therewith, stop motion mechanism, means for actuating said stop motion mechanism upon the failure of the reinforcing yarn to engage and feed along with the main yarn or upon the failure of the reinforcing yarn while being fed in.

7. A machine of the character described comprising in combination, main yarn-feeding mechanism, reinforcing yarn-feeding mechanism, means for automatically causing the reinforcing yarn to engage the main yarn and be fed along therewith, stop motion mechanism, a movable feeler supported out of actuating position by the reinforcing yarn when feeding, means actuated by the feeler when moved into actuating position to effect the operation of the stop motion mechanism, and means to hold the feeler out of actuating position until the reinforcing yarn is brought into position to engage the main yarn and thereupon to release the feeler whereby upon the failure of the reinforcing yarn properly to engage the main yarn and be fed along therewith or upon subsequent failure of the reinforcing yarn, the feeler will be moved into actuating position.

8. A machine of the character described comprising in combination, main yarn-feeding mechanism, reinforcing yarn-feeding mechanism, means for automatically causing the reinforcing yarn to engage the main yarn and be fed along therewith, stop motion mechanism, a movable feeler supported out of actuating position by the reinforcing yarn when feeding, means actuated by the feeler when moved into actuating position to effect the operation of the stop motion mechanism, and means to hold the feeler out of actuating position until the reinforcing yarn is brought into position to engage the main yarn and thereupon to release the feeler whereby upon the failure of the reinforcing yarn properly to engage the main yarn and be fed along therewith, the feeler will be moved into actuating position.

9. A machine of the character described comprising a main yarn-feeding mechanism, a reinforcing yarn feeding mechanism, means for automatically causing the reinforcing yarn to engage the main yarn to feed along therewith, stop motion mechanism, a pivotally mounted feeler supported from

dropping by the reinforcing yarn when feeding and acting when dropped to actuate the stop motion mechanism, a latch to engage the feeler and support it from dropping, and means acting to disengage the latch from the feeler when the reinforcing yarn is brought into position to engage the main yarn whereby unless the reinforcing yarn has properly engaged the main yarn, the feeler drops and actuates the stop motion mechanism.

10. A machine of the character described comprising a main yarn-feeding mechanism, a reinforcing yarn feeding mechanism, means for automatically causing the reinforcing yarn to engage the main yarn to feed along therewith, stop motion mechanism, a pivotally mounted feeler supported from dropping by the reinforcing yarn when feeding and acting when dropped to actuate the stop motion mechanism, a latch to engage the feeler and support it from dropping, and means acting to disengage the latch from the feeler when the reinforcing yarn is brought into position to engage the main yarn whereby unless the reinforcing yarn has properly engaged the main yarn, or upon subsequent failure of the reinforcing yarn, the feeler drops and actuates the stop motion mechanism.

11. A machine of the character described comprising in combination, main yarn feeding mechanism, reinforcing yarn feeding mechanism, means for automatically bringing into action said reinforcing yarn feeding mechanism, stop motion mechanism, normally inactive means for actuating said stop motion mechanism, and means for rendering said actuating means active upon the coming into action of said reinforcing yarn feeding mechanism to cause said actuating means to actuate the stop motion mechanism upon the failure of the reinforcing yarn to feed in.

12. A machine of the character described, comprising in combination, main yarn feeding mechanism, reinforcing yarn feeding mechanism, means for automatically bringing into action said reinforcing yarn feeding mechanism, stop motion mechanism, normally inactive means for actuating said stop motion mechanism, and means for rendering said actuating means active upon the coming into action of said reinforcing yarn feeding mechanism to cause said actuating means to actuate the stop motion mechanism upon the failure of the reinforcing yarn to feed in, or upon the failure of the reinforcing yarn while being fed in.

13. A machine of the character described, comprising in combination, main yarn feeding mechanism, reinforcing yarn feeding mechanism, means for automatically causing the reinforcing yarn to engage and be tied to the main yarn to feed along there-

with, stop motion mechanism, normally inactive means for actuating said stop motion mechanism, and means for rendering said actuating means active upon the coming into 5 action of said reinforcing yarn feeding mechanism to cause said actuating means to actuate the stop motion mechanism upon the failure of the reinforcing yarn to engage and be tied to and fed along with the main 10 yarn.

14. A machine of the character described, comprising in combination, main yarn feeding mechanism, reinforcing yarn feeding mechanism, means for automatically causing 15 the reinforcing yarn to engage and be tied to the main yarn to feed along therewith, stop motion mechanism, normally inactive means for actuating said stop motion mechanism, and means for rendering said 20 actuating means active upon the coming into action of said reinforcing yarn feeding mechanism to cause said actuating means to actuate the stop motion mechanism upon the failure of the reinforcing yarn to engage and be tied to and fed along with the main 25 yarn, or upon the failure of the reinforcing yarn while being fed in.

15. A machine of the character described, comprising in combination, main yarn feeding mechanism, reinforcing yarn feeding mechanism, means for automatically causing 20 the reinforcing yarn to engage the main yarn to feed along therewith, stop motion

mechanism, normally inactive means for actuating said stop motion mechanism, and 35 means for rendering said actuating means active upon the coming into action of said reinforcing yarn feeding mechanism to cause said actuating means to actuate the stop motion mechanism upon the failure of 40 the reinforcing yarn to engage and feed along with the main yarn.

16. A machine of the character described, comprising in combination, main yarn feeding mechanism, reinforcing yarn feeding 45 mechanism, means for automatically causing the reinforcing yarn to engage the main yarn to feed along therewith, stop motion mechanism, normally inactive means for actuating said stop motion mechanism, and 50 means for rendering said actuating means active upon the coming into action of said reinforcing yarn feeding mechanism to cause said actuating means to actuate the stop motion mechanism upon the failure of 55 the reinforcing yarn to engage and feed along with the main yarn, or upon the failure of the reinforcing yarn while being fed in.

In testimony whereof, I have signed my 60 name to this specification, in the presence of two subscribing witnesses.

EDISON E. RANDALL.
